UNITED STATES PATENT OFFICE.

JAMES W. C. RHIND, OF SAN FRANCISCO, CALIFORNIA, ASSIGNOR OF ONE-TENTH OF HIS RIGHT TO DOUGLAS WOOLEY, OF SAME PLACE.

AUTOMATIC SWITCH FOR WIRE-ROPE RAILROADS.

SPECIFICATION forming part of Letters Patent No. 228,932, dated June 15, 1880.

Application filed April 5, 1880. (No model.)

To all whom it may concern:

Be it known that I, JAMES W. C. RHIND, of the city and county of San Francisco, and State of California, have invented an Automatic Switch for Wire-Rope Railroads; and I hereby declare the following to be a full, clear, and exact description thereof.

The object of my invention is to provide an automatic switching apparatus for that class of railroads known as "wire-rope" railroads, where the power of propulsion is imparted by means of an endless rope.

In the cable or wire-rope railroads the endless rope runs down the center of one line of track and up the center of the other under the surface of the street in a suitable tube, power being applied to the rope by engines at any convenient point. A dummy or small car coupled to the passenger-car is provided with what is known as a "gripe." This gripe passes down through a slot in the center of the roadway, and is provided with mechanism operated from above, by means of which it may be connected with or detached from the moving rope at will, so as to stop or start the car. This gripe projects down below the level of the roadway at all times, and the dummy on which it is placed precedes the car.

At the end of the line it is necessary for the car to be passed ahead of the dummy, and the car must therefore be switched off to the other track first, and the dummy follow it, so as to come in front on the return trip. The way in which this is done at present is, that just before reaching the switch the car and dummy are disengaged, and the dummy passes on a short distance ahead over the closed switch-point. As soon as it passes an attendant shifts the switch, which turns the following passenger-car off onto the up track, and it runs on down to the end of the line, the dummy having meantime been stopped. The dummy, with its gripe drawn up clear of the endless cable, then crosses over by a curved track or another switch and comes in behind the car, so as to be ahead of it in starting up again.

The switch over which the passenger-car goes must be closed to allow the dummy first to pass down the line, and then opened to al-

low the car to come over to the other track. 50 The ordinary methods of operating switches automatically will not answer with these cable roads, since there is no room for automatic mechanism, the gripe reaching from the dummy needing a slot through everything in order to pass along, its lower end being always below the street-level. An attendant has therefore to run the switch.

My invention consists in providing a movable switch, which is so connected by suitable 60 levers under the level of the track that the said levers may be automatically moved at the proper time by means of the downward-projecting gripe, so as to open and close said switch at the proper time for both dummy and 65 car, as is more fully described in the accompanying drawings, in which—

Figure 1 is a perspective view of my device. Fig. 2 is a top view of the same. Fig. 3 is a modification. Fig. 4 is a transverse section. 70

Let A represent the right-hand or downward line of track, near the end of the road, where the transposition of car and dummy with relation to each other is made. A bar, B, has a pin, b, which connects with the switch a on the 75 surface. A long straight lever, C, is suitably pivoted to the bar B, and in front of this another lever, C', curved as shown at c, is also connected with said bar B.

Now, as the dummy D comes down the 80 track in front of the car, the car and dummy are disconnected, the dummy going on ahead, the car being slowed down. As the dummy passes on the gripe d strikes the long lever C, and, through the medium of the bar B and its 85 pin b, shifts the switch a point to the branch, and holds it while the dummy is moving on. As soon as the dummy passes the switch and goes clear of it, then the same gripe strikes the curve c of the other lever, C', which throws 90 the switch open for the siding, and the car coming on down the main track is switched off onto its proper track. The car then going down on its proper track to the end, the dummy goes by a curve in the track and comes 95 in front of the car, the transposition being thus effected without the necessity of any one handling the switch. The next dummy which

comes down the line, by its gripe *d* striking the lever *C*, shifts the switch and again replaces it, as described.

On some of the cable roads the cars of other lines, drawn by horses, pass over the same line of rails or cross off from said lines. It becomes, then, the duty of the cable road to open or close the switches, so the cars of the other line may have unobstructed passage without having to move switches. My system of moving the switches by means of the levers and impinging gripe is here applicable also. I have shown this in Fig. 3. Here one of the levers is extended in length, and the gripe moves the levers so as both to close and open the switch. As the dummy and car come along the track *A'* the gripe, striking the upper lever, closes the cross-line switch *a'* and holds it closed while said dummy and car pass on, the same as hereinbefore described. After both dummy and car have passed, the gripe strikes the lever *C'* at some distance from the switch and opens said switch *a'* for the horse-car line, leaving it open until the next cable car and dummy come on and repeat the operation. In this way the line is always open for the horse-car line, the dummy and gripe of the cable line closing its switch at the time it is passing, and immediately opening it for the

other road as soon as both dummy and car have passed. This is done automatically, no attendants being required to care for the switches, the wire road maintaining its right of way and opening the switches for the other line without fail. Of course, on these cable roads the cars can only travel in one direction on each line of track, as the cable is moving up one line and down the other continually.

Having thus described my invention, what I claim as new, and desire to secure by Letters Patent, is—

In a cable railroad in which the cars are provided with a downward-projecting gripe, *d*, so as to be driven by means of an endless rope beneath the roadway, the levers *C C'*, 45 placed below the ~~base~~ of the rails and connected with the ~~switch~~ and adapted to be moved by impingement of said gripe *d*, whereby said switch is automatically opened and closed, substantially as and for the purpose herein described.

In witness whereof I have hereunto set my hand.

JAMES W. C. RHIND.
